PROJECTILE

Harry J. Nichols, New York, N. Y.

Application June 24, 1942, Serial No. 448,291

9 Claims. (Cl. 102—52)

1

This invention relates primarily to minor-calibre, armor-piercing, explosive projectiles especially designed for use against tanks, gun shields, destroyers, and similar light-armored structures.

The particular object of the invention is to provide a practical projectile of simple construction which is more highly efficient in penetrating armor at oblique angles as well as substantially normal angles of attack.

The contest between projectiles and armor is notably one in which the advantage has passed from one side to the other over the years. Improvements in projectiles have called for more effort and ingenuity in the development of armor. Eventually the improvements in armor have spurred the projectile makers to greater efforts, and so on. At present it appears that light armor has been improved relative to minor-calibre projectiles to such a degree that a radical improvement in the armor piercing ability of such projectiles is needed to restore the balance.

It is accordingly a further major object of this invention to provide a radical improvement in the armor piercing properties of minor-calibre projectiles without radically changing their form nor increasing their cost, nor requiring modification of the gun for firing such projectiles.

Another object is to utilize the power of an explosive charge carried within the projectile body to increase the armor piercing properties of a projectile.

Another object is to provide a construction of armor-piercing projectiles in which the projectile body functions during penetration as an inverted gun thereby to enable an explosive charge carried by the projectile to propel the projectile through relatively thicker armor at any striking velocity than has heretofore been possible.

Another object is to provide a novel construction of armor-piercing projectiles introducing a new principle for increasing the penetrating ability of a projectile in which an inertia member is discharged backwards by an explosive driving charge during impact of the projectile with the target, and the reaction from said member augments the forward momentum of the projectile.

Other objects will be in part obvious from the annexed drawings and in part thereafter indicated in connection therewith by the following analysis of this invention.

This invention accordingly consists in the features of construction, combination of parts, and in the unique relation of the members and in the relative proportioning and disposition thereof, all as more completely outlined herein.

2

To enable others skilled in the art fully to comprehend the underlying features of this invention, that they may embody the same by the numerous modifications in structure and relation contemplated by the invention, drawings depicting three preferred embodiments of the invention form a part of this disclosure, and in such drawings like characters of reference denote corresponding parts throughout the several views, in which—

Fig. 1 shows in longitudinal cross section a projectile embodying the new principle, termed the reaction principle, of augmenting the penetrating ability of armor-piercing projectiles;

Fig. 2 shows in a similar manner another projectile construction embodying this novel principle of the invention; and

Fig. 3 shows yet another projectile construction embodying this novel principle of the invention.

Referring now to the drawings in detail, and particularly to Fig. 1, a pointed head 10 and cylindrical hollow body 11 of a projectile there shown are integral, providing a main projectile structure of monobloc form of strong and massive proportions. Preferably the main projectile structure is made of the highest quality alloy projectile steel and is heat treated for suitable hardness of the head 10, and thereafter the body portion 11 is drawn back incrementally towards the base to provide a tough, elastic, non-shattering barrel portion. The body 11 is provided with an axial bore 12 and a counter-bore 13 formed from the base end, providing a forward explosive chamber in which an explosive driving charge 14 is loaded and an after cavity in which, as herein shown, a relatively light base plug 15, called the reaction plunger, is fitted tightly but slidably. A gasket 16 is preferably fitted between a shoulder 17 of plunger 15 and the body

11 to insure a gas-tight joint between those members while holding them together. The body is fitted with a rotating band 18, preferably electro-deposited in place as described in my United States Patent No. 2,283,224, dated May 19, 1942.

It should be noted that the monobloc construction just described provides a projectile whose strength is in no way decreased by the addition of the driving charge 14 and the reaction plunger 15. Also the construction of the invention overcomes an inherent limitation of compound projectiles heretofore proposed, namely, the tendency to fracture or separation of the main component parts of the projectile upon impact with armor.

For best results in penetrating armor, the head 10 may be fitted with a cap 20 (Fig. 3) of softer

metal than the head, and attached securely thereto in any desired manner, as for example by soldering. The cap 20 and its function in aiding the projectile to penetrate hard armor being well known, no detailed description is considered necessary. With respect to the present invention, the provision of an armor-piercing cap 20 is to be considered an optional feature. Likewise, a windshield 21 of thin metal as shown in Fig. 3, or of moulded plastic as shown in Figs. 1 and 2, may be fitted to reduce the air drag in flight, all being of well known construction.

The reaction plunger 15 is preferably provided with an inner bore 22, and a counterbore 23. A metal exploder ball 24 is securely seated in the bottom of the bore 22 by cementing, soldering, or other suitable retaining means. A charge of detonating explosive 25, termed the detonator charge, is preferably enclosed in a metal capsule 26 and is assembled in the counterbore 23. Preferably a disc or wad 27 is assembled between the driving charge 14 and the inner end 28 of plunger 15.

The operation of the projectile shown in Fig. 1 on impact with armor is as follows: On striking and as the head 10 penetrates into the armor, the exploder ball 24 is dislodged from its seat and flies forward to strike the detonator charge 25, exploding same. This charge in turn detonates the driving charge 14, and the combined gases of the two produce an impulsive pressure amounting to a powerful blow on the walls of the chamber of the projectile. This pressure acts to drive head 10 forwardly and reaction plunger 15 rearwardly (in relation to head 10) with great force. Following well known laws of physics the kinetic blow of the driving charge and, the reaction from plunger 15 produce a powerful forward acting force on the main structure of the projectile augmenting its momentum due to forward flight, and thereby increasing its ability to perforate the armor plate.

It is to be noted that the exploder ball provides a means of variably timing the explosion of the driving charge in inverse relation to the degree of impact. In other words, on heavy impact the explosion occurs more quickly than on light impact, because the ball is thrown forward more quickly, and on heavy impact, the critical instant determining perforation or non-perforation occurs at an earlier stage of penetration.

For purposes of the invention, a detonatable explosive charge of low brisance herein termed a driving charge is preferred. The explosive action desired is that which produces the maximum velocity of ejection of the reaction plunger 15 without or before bursting the projectile body. Explosives of the nitroglycerine-nitrocellulose type, as for example cordite, can be used in some cases. Explosives of this class are of greatly reduced shattering power as compared to the usual shell-charge explosives such as T. N. T. or picric acid. As an alternative to cordite or the like, mixtures of ammonium nitrate or perchlorate, aromatic nitro-compounds, and carbonaceous materials can be utilized to obtain graduated degrees of brisance. Hence it is evident that by following the teaching of this invention, a variety of driving charges can be produced to cause high velocity ejection of the reaction plunger in various sizes, proportions, and strengths of projectiles. Experiments have indicated that under proper conditions a detonatable driving charge can eject the reaction plunger at velocities of

several thousand feet per second, imparting a powerful reaction to the projectile body itself.

Referring now to Fig. 2, in the embodiment there shown, the forward reduced portion of the reaction plunger 30 is left solid, but a groove 31 is cut into the neck portion thereof to form a head 32. The purpose of the groove 31 is to provide means for predetermining the degree of impact at which explosion of the driving charge 14 occurs. The deeper the groove and hence the weaker the neck, the lesser the degree of impact at which the head 32 will detach itself and produce an explosion of the driving charge.

On striking armor of sufficient resistance, the head portion 32 of the reaction plunger will separate and plunge forward with great force, impacting and exploding the driving charge 14. The latter ejects the entire plunger 30 rearwardly with great force. The reaction force augments the forward velocity of the projectile proper as previously described.

Since the driving charge 14 in Fig. 2 is to be exploded by impact of the head 32, rather than by the customary detonator, the proper selection of the explosive for that charge requires consideration. For example, the relative sensitiveness to impact of representative shell-charge explosives has been authoritatively given as approximately:

30	Trinitro-cresol	30
	Tetryl	40
	Picric acid	50
	T. N. T.	70
35	Ammonium nitrate	80
	Dinitrophenol	150

(In this tabulation the smaller the number the greater the sensitivity.)

40 Hence, by choosing explosives of proper sensitivity the degree of impact to produce explosive action can be predetermined by those familiar with the subject.

Referring now to Fig. 3, in the embodiment therein shown the reaction plunger 40 is a solid piece of metal of sufficient strength to resist heavy impacts, but in this embodiment the driving charge 41 itself is of a nature and form to produce self-detonation on heavy impact with armor. To that end the explosive charge is preferably in two increments 41-42 of different sensitivity, the most sensitive increment preferably being loaded in the forward portion of the cavity 43 as shown, or the charge may be a mixture of sensitive and insensitive explosive materials, or a single sensitive explosive compound may be employed. For example, in the preferred form shown, the forward explosive increment 42 may be a sensitive explosive, such as tetryl, while an explosive of lower brisance, such as an ammonal, indicated at 41, is preferred for the rear increment. By suitable choice of the explosive components following the teaching of the invention, the degree of impact at which self-detonation of the driving charge will occur can be determined as desired.

It is to be noted that the embodiments shown in Figs. 2 and 3 enable a tracer to be housed in the base of the reaction plunger.

It may at first thought appear that the augmentation of the penetrating force by the explosive force of the self-contained driving charge is hardly enough to be important. But it has been found by actual experiment with projectiles fired against armor plate that a small increase

of momentum in the vicinity of the critical velocity of perforation has an extraordinary effect with respect to ability to perforate. For example, if a particular projectile just failed to perforate a particular plate at 2000 f. s., an increase of striking velocity of 50 f. s. or only 2½% will not only enable the projectile to perforate the plate, but the residual velocity of the projectile after perforation will be several hundred feet per second. Also, experiments have shown that high explosive charges under favorable conditions can drive the head forward with unbelievable force. At critical and sub-critical velocities, the additional force provided by the explosive driving charges, utilized as provided for by the invention, will have an entirely unexpected effect in increasing the perforating properties of a projectile.

It will be evident from the above that the present invention provides simple and practical means for improving the armor-piercing ability of projectiles of the class described.

Without further analysis the foregoing will so fully reveal the gist of this invention that others can, by applying current knowledge, readily adapt it for various applications without omitting certain features that, from the standpoint of the prior art, fairly constitute essential characteristics of the generic or specific aspects of the invention, and therefore such adaptations should and are intended to be comprehended within the meaning and range of equivalency of the following claims.

I claim:

1. An explosive armor-piercing projectile comprising, in combination, a pointed head portion adapted to pierce armor and a body portion integral therewith having an axial bore and comprising a non-shattering explosive chamber, a high explosive driving charge loaded in said chamber, a rearwardly ejectable base closure member mounted slidably in said bore and adapted to utilize by rearward movement part of the explosive force of said driving charge, and means for detonating said driving charge with relation to the degree of impact of the projectile with armor, thereby to augment the forward momentum of said head and body during the penetration of armor.

2. An explosive armor-piercing projectile comprising, in combination, a monobloc head and hollow body having an axial bore, a high explosive driving charge loaded in said bore, and lesser ejectable member slidably mounted in said bore rearwardly of said charge and adapted by rearward movement to cause the explosion of said charge to react upon and augment the forward momentum of said head and body upon impact of said head with armor.

3. In explosive armor-piercing projectiles including a monobloc head and hollow body, means for augmenting the forward momentum of said head and body on impact with armor comprising a high explosive driving charge of low brisance sealed within the projectile body, a rearwardly ejectable base closure member mounted slidably in said bore rearwardly of said charge in operative relation thereto, and detonating means for exploding said charge in exactly executed variable relation to the impact of the projectile with armor.

4. In explosive armor-piercing projectiles, in combination, a monobloc head and hollow body structure, and means for augmenting the armor-piercing ability of said structure comprising a

high explosive charge of low brisance sealed bodily within said body, a base closure member mounted rearwardly slidably in said body and adapted to be ejected at high velocity therefrom by said charge thereby to drive the head and body structure forwardly by reactive force, and detonating means for said charge adapted to cause the explosion of said charge in inverse time relation to the degree of impact of said head with armor.

5. In explosive armor-piercing projectiles, a pointed head and relatively massive hollow body member integral therewith constituting a combined armor-piercing projectile and secondary gun, a charge of high explosive of low brisance sealed within said body and constituting the propulsive charge of said secondary gun, a lesser ejectable base closure member constituting a relatively smaller sub-projectile adapted to be ejected rearwardly by said charge, thereby to augment by means of reactive force the forward momentum of said head and body, and means for detonating said high explosive in predetermined, exact relation to the penetration of armor.

6. An explosive armor-piercing projectile comprising, in combination, a pointed armor-piercing head and a massive body integral therewith having an axial bore including an explosive chamber, a charge of high explosive of low brisance loaded in said chamber, and an ejectable base closure means for said body including a reaction plunger mounted in said bore rearwardly of said charge and adapted to be ejected rearwardly by said charge thereby to augment reactively the armor piercing ability of said head and body, and means for detonating said charge in predetermined relation to the impact of said head with armor.

7. In an explosive armor-piercing projectile including an armor-piercing head and a body portion integral therewith having an internal explosive chamber, means for augmenting the armor-piercing ability of said head including a rearwardly ejectable base closure for said explosive chamber and an explosive charge within said chamber comprising a plurality of explosive components adapted in combination to explode on heavy impact with armor, one of said components being insensitive to impact and adapted to cushion the other components against premature explosion when said projectile is fired in a gun.

8. An explosive armor-piercing projectile comprising, in combination, an armor-piercing head portion and a relatively massive body portion integral with said head portion having a relatively small explosive combustion chamber therein, an explosive propulsion charge contained wholly within said chamber, means positioned rearwardly of said charge for exploding the charge after impact and in predetermined relation to the instant of impact, and a plunger tightly fitting and slidably in the base of the body portion of the projectile, said plunger including a detachable forward portion adapted to move forwardly on impact to explode the propulsion charge within the combustion chamber.

9. An explosive armor-piercing projectile comprising, in combination, an armor-piercing head portion and a relatively massive body portion integral with said head portion having a relatively small explosive combustion chamber therein, an explosive propulsion charge contained wholly within said chamber, means positioned rearwardly of said charge for exploding the charge after impact and in predetermined rela-

tion to the instant of impact, and a plunger tightly fitting and slideable in the base of the body portion of the projectile, the means for exploding the propulsion charge including a detachable member associated with the plunger and adapted to move forwardly on impact to explode the propulsion charge within said chamber in predetermined relation to said impact.
